W. N. DOTY

FISH GRAB

Filed May 10, 1924

UNITED STATES PATENT OFFICE.

WILLIAM N. DOTY, OF CLARKSVILLE, IOWA.

FISH GRAB.

Application filed May 10, 1924. Serial No. 712,329.

To all whom it may concern:

Be it known that I, WILLIAM N. Doty, a citizen of the United States, residing at Clarksville, in the county of Butler and State of Iowa, have invented certain new and useful Improvements in Fish Grabs, of which the following is a specification, reference being had to the accompanying drawings.

10 This invention relates to gaffs such as are used in fishing, and particularly to what are known as fish grabs, that is instruments having spring actuated hooks for gaffing the fish after the fish has been caught by 15 hook and line.

The general object of the invention is to provide a very simple, readily operated and effective gaff of this character which is so constructed that the fish cannot possibly get 20 off the gaff after once being caught.

A further object is to provide a device 25 of this character which may be readily set and in which contact with the fish will cause the release of the jaws, the spring then 30 acting to force the jaws together with great force so as to properly gaff the fish.

Other objects have to do with the details of construction and arrangement of parts as will appear more fully hereinafter.

35 My invention is illustrated in the accompanying drawings, wherein:—

Figure 1 is an elevation of a fish grab constructed in accordance with my invention;

35 Figure 2 is a side elevation partly in section of the fish grab showing the jaws closed;

Figure 3 is a fragmentary view similar to Figure 2 but showing the jaws opened;

40 Figure 4 is a fragmentary section at the intersection of one of the jaws with the latch, showing the spring for urging the latch downward;

Referring to these drawings, it will be seen 45 that 10 designates the shank of the gaff, this shank at one end being provided with a socket or ferrule 11. A nut or like member 12 constituting a shoulder is disposed at one end of this shank at its junction with 50 the ferrule 11. A pole 13 may be inserted in the ferrule of any desired length.

The end of the shank remote from the shoulder 12 is bifurcated, as at 14, and pivoted in this bifurcated shank are the two 55 jaws 15 and 16. These jaws are substantially alike, each jaw consisting of a straight

portion extending out fully the length of the jaw, and then the jaws are curved, as at 17, and terminate in sharp points 18. Just below the point where the jaws curve outward or bow outward the jaws are thickened and longitudinally slotted, as at 19, and the jaw 16 is formed just below this slot with the outwardly projecting stop or stud 20. Pivotaly mounted in one of these slots, as by means of the pivot 21, is the latch 22, which latch is somewhat arcuate in shape and at one end is cut away so as to accommodate a spring 23 which acts to force the latch outward. The opposite end of the latch passes through the slot 19 in the jaw 16 and is provided with the somewhat elongated head 24. Inward of this head the upper face of the shank is cut away so as to provide a shoulder 25 which, when the jaws are opened, bears against the inner face of the jaw 15 and thus holds the jaws spread apart, the spring 23 acting to force the latch upward and the shoulder in operative engagement 80 with the jaw 16.

Slidably mounted upon the shank 10 is a sleeve 26 which is formed with a shoulder 27 having outwardly projecting handle 28, and disposed between the shoulder 12 and the shoulder 27 is a relatively strong coiled compression spring 29. The upper end of this sleeve is longitudinally slotted at diametrically opposite points, as at 30, and at the extremity of the sleeve there is provided 90 a transversely extending pin 31 extending at right angles to the plane of the slots 30. When the jaws are closed, as shown in Figure 2, the stop lug 20 bears against this pin 31 and also bears against the opposite jaw 95 so that the jaws will not strike.

In order to set this instrument, the spring may be forced down by means of the handles 28, which will loosen the jaws, and then the jaws may be moved apart from each other by any suitable means, as by pulling the jaws apart until the shoulder 25 engages against the jaw 16. If now the implement be forced against a fish as, for instance, against the head of a fish which has 105 been caught on a line which is being pulled in, the latch 22 will be forced inward, thus releasing the jaws, and the spring 29 will force the sleeve upward, causing the jaws to close with great force and impaling the 110 fish upon the pointed jaws.

It is also possible to set this fish grab by

passing the jaws through a slotted board and pressing down on the handle or pole 13. Another manner of setting the construction is to hold the instrument firmly in 5 one hand with the ferrule placed between the two forefingers of the other hand, with the lugs at the opposite end, and pull against the coiled spring to set it.

This invention is very simple, may be 10 easily operated, is easily released by a very slight pressure against the head of a fish, and has been found thoroughly effective in practice. It will be noted that the nut 12 is adjustable so as to increase or decrease 15 the tension of spring 29.

I claim:—

1. A fish grab of the character described comprising a shank, a pair of jaws pivoted to the upper end of the shank, said jaws 20 being formed with outwardly curved portions terminating in points, the jaws being slotted, a latch pivoted in the slot of one of said jaws and extending slidingly through the slot of the other jaw, the latch having a 25 shoulder engaging the last named jaw to thereby hold the jaws expanded, a spring urging the latch outward into its latching position, a sleeve mounted upon the shank and having handles whereby the sleeve may 30 be shifted, and a spring operatively supported at one end upon the shank and at the other end operatively bearing against said sleeve to urge it outward.

2. A fish grab of the character described 35 comprising a shank, a pair of jaws pivoted to the upper end of the shank, said jaws being formed with outwardly curved portions terminating in points, the jaws being slotted, a latch pivoted in the slot of one 40 of said jaws and extending through the slot of the other jaw, the latch having a shoulder of the other jaw, the latch having a shoulder engaging the last named jaw to thereby hold the jaws expanded, the sleeve being longitudinally slotted at its extremity and the

bases of the jaws passing through said slots, 45 there being a pin extending through the extreme end of the slotted sleeve outward of the jaws and one of said jaws having a stop lug which, when the jaws are closed, engages against said pin, and a spring surrounding the shank and operatively supported upon the shank at one end and at the other operatively bearing against said sleeve and urging it outward, the sleeve being provided with handles whereby it may be 55 shifted inward against the force of said spring.

3. A fish grab of the character described comprising a shank bifurcated at one end, a pair of jaws pivoted in said bifurcated 60 end of the shank, each of said jaws having a straight portion and an outwardly curved portion terminating in a point, the straight portions of the jaws being slotted, a latch pivoted in one of said slots and extending through the other slot, the latch being provided at its free end with a head and with a shoulder on its outer edge, a spring urging the latch outward, a sleeve surrounding the shank, the sleeve at its 65 outer end being slotted to accommodate said jaws and one of the jaws being provided with an inwardly projecting stop and the sleeve being provided with a transversely extending pin engaging said stop when the 70 jaws are closed and the sleeve forced outward to thereby limit the outward movement of the sleeve, the shank being provided at one end with a shoulder, and a spring disposed between the shoulder and 75 the sleeve and urging the sleeve outward, the sleeve being provided with handles whereby it may be drawn inward against the action of said spring.

In testimony whereof I hereunto affix my 85 signature.

WILLIAM N. DOTY,
